UNITED STATES PATENT OFFICE

169,561

TAMPER FOR CHOPPING MACHINES

Horace J. Raymond, deceased, late of Concord, Calif., by Gladys V. Raymond, assignee, Concord, Calif.

Application December 29, 1951, Serial No. 17,854

Term of patent 14 years

(Cl. D44—29)

To all whom it may concern:

It being known that Horace J. Raymond, deceased, late a citizen of the United States and a resident of Concord, State of California, has invented a new, original, and ornamental Design for a Tamper for Chopping Machines, of which the following is a specification, reference being had to the accompanying drawings, forming part thereof, wherein

Figure 1 is a side and bottom perspective view of a tamper, embodying the present new design,

Figure 2 is a side elevation of the tamper,

Figure 3 is a top view of the tamper, and

Figure 4 is a side and top perspective view of the tamper.

What is claimed is:

The ornamental design for a tamper for chopping machines, substantially as shown.

GLADYS V. RAYMOND.

Assignee of the estate of Horace J. Raymond, deceased.
